(57) **ABSTRACT**

An adjustable rehabilitation and exercise device, including a rotary member having a plurality of elongated and spaced apart elongated open-ended slots defined thereon, each slot including a plurality of enlargements along the length thereof. A mount is selectively and movably positionable on a selected one of the slots of the rotary member to select an angular location of the mount. The mount includes a slide member movably positionable along the selected slot to a selected radial location along the selected slot to select a radial location of the mount relative to the hub of the rotary member. The mount includes a movable pin having an enlarged head. The pin is positionable to selectively engage the enlarged head thereof within the enlargements of the slot so as to lock the position of the mount along the slot. A patient engagement member is connectable to the mount and movable with the mount.

**ADJUSTABLE REHABILITATION AND
EXERCISE DEVICE**

FIELD

This disclosure relates to the field of rehabilitation devices. More particularly, this disclosure relates to adjustable rehabilitation devices having improved connection and adjustability of patient engagement members.

BACKGROUND

Improvement is desired in the construction of adjustable rehabilitation and exercise devices. Adjustable rehabilitation and exercise devices having pedals on opposite sides and adjustably positionable relative to one another have been proposed. However, such designs require improvement due to the fact that the pedals tend to not remain securely mounted and detach, wobble and the like. In addition, it is desirable to provide for an adjustable rehabilitation or exercise device that is capable of providing both powered motion or user initiated motion without the need for separate devices.

Accordingly, in one aspect, the disclosure provides an adjustable rehabilitation and exercise device having improved structure for locating patient engagement members.

SUMMARY

The disclosure provides an adjustable rehabilitation and exercise device.

In one aspect, an adjustable rehabilitation and exercise device includes a rotary member having a plurality of elongated and spaced apart elongated open-ended slots defined thereon, each slot including a plurality of enlargements along the length thereof. A mount is selectively and movably positionable on a selected one of the slots of the rotary member to select an angular location of the mount.

The mount includes a slide member movably positionable along the selected slot to a selected radial location along the selected slot to select a radial location of the mount relative to the hub of the rotary member. The mount includes a movable pin having an enlarged head.

The pin is positionable to selectively engage the enlarged head thereof within the enlargements of the slot so as to lock the position of the mount along the slot. A patient engagement member is connectable to the mount and movable with the mount.

BRIEF DESCRIPTION OF THE DRAWINGS

Further advantages of the disclosure are apparent by reference to the detailed description when considered in conjunction with the figures, which are not to scale so as to more clearly show the details, wherein like reference numbers indicate like elements throughout the several views, and wherein:

FIGS. 1A and 1B are perspective views of an adjustable rehabilitation and exercise device according to the disclosure configured to have adjustably positionable patient engagement members.

FIGS. 2-10 show a wheel system for adjustably positioning a patient engagement member.

FIGS. 11 and 12 show an adjustable mount of the wheel system.

2

DETAILED DESCRIPTION

With initial reference to FIGS. 1A-1B, there is shown an adjustable rehabilitation and exercise device 10 having patient engagement members, such as pedals 12 on opposite sides that are adjustably positionable relative to one another, but securely mounted according to the disclosure to provide a more secure mounting that avoids disconnection, wobbling and the like often experienced with prior devices.

10 The device 10 includes a rotary device such as a wheel 14 or flywheel or the like rotatably mounted such as by a hub to a frame 16 or other support. The pedal 12 is configured for interacting with a patient to be rehabilitated and may be configured for use with lower body extremities such as the feet, legs, or upper body extremities such as the hands, arms, and the like. For example, the pedal 12 may be a conventional bicycle pedal of the type having a foot support rotatably mounted onto an axle with bearings. The axle has exposed end threads for engaging a mount on the wheel 14 to locate the pedal on the wheel 14.

15 The wheel 14 may be configured to have both pedals 12 on opposite sides of a single wheel. However, a preferred construction, as seen in FIGS. 1A and 1B shows a pair of the wheels 14 spaced apart from one another but interconnected to a flywheel or the like.

20 The rehabilitation and exercise device 10 of FIGS. 1A-1B may take the form as depicted of a traditional exercise/rehabilitation device which is more or less non-portable and remains in a fixed location, such as a rehabilitation clinic or medical practice.

25 Alternatively, the device 10 may be configured to be smaller and more portable unit so that it is able to be easily transported to different locations at which rehabilitation or treatment is to be provided, such as a plurality of patient's homes, alternative care facilities or the like.

30 With reference to FIGS. 2-10, there is shown a wheel system 20 having a patient engagement member, such as a pedal corresponding to the pedal 12 above, adjustably mountable on a wheel 24 by an adjustable mount 26.

35 FIG. 2 shows a front side of the wheel 24, and FIG. 3 shows a rear side of the wheel 24. The wheel 24 is a disk configured to include a plurality of spaced apart elongated slots 24a formed through the thickness of the wheel 24 to receive the mount 26. The slots 24a include enlargements

40 24aa. A pair grooves 24b are formed on each side of the wheel 24 parallel to and on opposite sides of the slots 24a. The wheel 24 also includes a central mounting aperture 24c to provide a hub for rotatably mounting of the wheel 24 to the device 10. Material of the wheel 24 may be removed to 45 provide openings 24d to provide aesthetics and for reducing the weight and the cost of the wheel 24. The slots 24a and the grooves 24b desirably have open ends to facilitate installation and removal of the mount 26.

50 The mount 26 includes a front sliding member 26a and a rear sliding member 26b. The sliding members 26a and 26b each include pegs 26c on their inner sides for slidably engaging the grooves 24b of the wheel 24. The sliding members 26a and 26b are fixed together as by a threaded fastener 26d that extends through a bore 26dd of the sliding

55 member 26b and into a corresponding post 26e of the sliding member 26a (FIG. 10). The sliding member 26a includes a receiver 26f configured to receive an axle of the pedal or other patient engagement member. A lock pin 26g is provided to extend through aligned bores 26h of the sliding members 26a and 26b and pass through one of the enlargements 24aa of the slot 24a to selectively lock the position of the mount 26, as explained more fully below.

The mount 26 is slidable along the slot 24a and the grooves 24b when the lock pin 26g is not installed. The lock pin 26g is installed through the aligned bores 26h and the enlarged head 26gg is passable into the slot 24a when the head 26gg is aligned with one of the enlargements 24aa, thus seating the head 26gg in one of the enlargements 24aa, and locking the mount 26 in position. The position of the mount 26 may be adjusted by alternating the seating of the head 26gg in the various enlargements 24aa of the slot 24a. In this manner, the sliding mount 26 may be moved along the slot 24a to change its radial location on the wheel 24.

The mount 26 is configured to stably locate a pedal or other patient engagement member and eliminate wobble and the like associated with conventional devices. In addition, the mount 26 is also configured to advantageously enable substantially incremental adjustment of the position of the mount.

The mount 26 cooperates with the slot 24a and the grooves 24b to adjustably position the mount 26, and hence the pedal, relative to the hub of the wheel 24. Further, the availability of a plurality of slots 24a enables a user to select which slot 24a for installation of the mount 26. Thus, in combination, the mount 26 and the slots 24a with their respective grooves 24b enable radial and angular adjustment of the position of the pedal or other patient engagement member. When this manner of adjustment is used for both of the pedals on opposite sides of the device 10, it will be appreciated that the pedals, or other patient engagement members, may be adjustably positioned relative to one another angularly, with each pedal being radially adjustable relative to the hubs of the wheels.

The foregoing description of preferred embodiments for this disclosure has been presented for purposes of illustration and description. It is not intended to be exhaustive or to limit the disclosure to the precise form disclosed. Obvious modifications or variations are possible in light of the above teachings. The embodiments are chosen and described in an

effort to provide the best illustrations of the principles of the disclosure and its practical application, and to thereby enable one of ordinary skill in the art to utilize the disclosure in various embodiments and with various modifications as are suited to the particular use contemplated. All such modifications and variations are within the scope of the disclosure.

The invention claimed is:

1. An adjustable rehabilitation and exercise device, comprising:

a rotary member having a plurality of elongated and spaced apart elongated open-ended slots defined thereon, each slot including a plurality of enlargements along the length thereof;

a mount selectively and movably positionable on a selected one of the slots of the rotary member to select an angular location of the mount, the mount including a slide member movably positionable along the selected slot to a selected radial location along the selected slot to select a radial location of the mount relative to a hub of the rotary member, the mount including a movable pin having an enlarged head, wherein the pin is positionable to selectively engage the enlarged head thereof within one of the enlargements of the slot so as to lock the position of the mount along the slot; and

a patient engagement member connectable to the mount and movable with the mount.

2. The device of claim 1, wherein the enlargements are uniformly spaced along the length of the slot.

3. The device of claim 1, further comprising grooves on opposite sides of the slot parallel to the slot, with the mount including pegs slidably disposed within the grooves.

4. The device of claim 1, wherein the slide member includes a front slide member and a rear slide member located on opposite sides of the rotary member.
